(57) **CLAIM**

The ornamental design for a coding matrix tool, as shown and described.

DESCRIPTION

A portion of the disclosure of this patent document contains material to which a claim for copyright is made. The copyright owner has no objection to the facsimile reproduction by anyone of the patent document or the patent disclosure, as it appears in the Patent and Trademark Office patent file or records, but reserves all other copyright rights whatsoever. FIG. 1 is a front first perspective view of the coding matrix tool, in unfolded configuration showing my new design; FIG. 2 is a rear perspective view thereof; FIG. 3 is a front elevation view of the first panel thereof; FIG. 4 is a front elevation view of the second panel thereof; FIG. 5 is a front elevation view of the third panel thereof; FIG. 6 is a front elevation view of the fourth panel thereof; FIG. 7 is a front elevation view of the fifth panel thereof; FIG. 8 is a rear elevation view of the fifth panel thereof; FIG. 9 is a rear elevation view of the fourth panel thereof; FIG. 10 is a rear elevation view of the third panel thereof; FIG. 11 is a rear elevation view of the second panel thereof; and, FIG. 12 is a rear elevation view of the first panel thereof. The broken lines in the drawings are for the purposes of illustrating environment only, and form no part of the claimed design.
